2 SHEETS—SHEET 2.

UNITED STATES PATENT OFFICE.

HAROLD J. DORRANCE, OF PITTSBURGH, PENNSYLVANIA.

OSTEOPATHIC-TREATMENT TABLE.

1,092,435.

Specification of Letters Patent.

Patented Apr. 7, 1914.

Application filed February 7, 1913. Serial No. 746,797.

To all whom it may concern:

Be it known that I, HAROLD J. DORRANCE, of Pittsburgh, in the county of Allegheny and State of Pennsylvania, have invented 5 certain new and useful Improvements in Osteopathic-Treatment Tables, of which the following is a specification.

The prime object of my invention is to provide a new and improved table, particularly designed for use by osteopathic practitioners and mechanical therapists.

A further object of the present invention is to provide a table of the class described including a fixed table member and a movable table member, the latter being designed 15 to be moved vertically both above and below a horizontal plane, and laterally relatively to the fixed member.

A still further object is to provide simple 20 and efficient means for supporting the movable table member and imparting thereto the desired movements relatively to the fixed table member.

In the accompanying drawings, which 25 illustrate an application of my invention; Figure 1 is a part elevational view and a part longitudinal sectional view, the section being taken on line I—I of Fig. 2; Fig. 2 is a top plan; and Fig. 3 is an end view.

30 As illustrated and as preferred, the table comprises a fixed member 1 supported by straight vertically extending legs 2 and by inclined bent legs 3.

The table construction includes a member 35 designed to be moved vertically relatively to the fixed table member 1, both above and below the horizontal plane of the fixed table member, and to be swung laterally thereof. As shown, this member is designated by the 40 numeral 4, and will hereinafter be referred to as the movable member or the movable table member. Interposed between the said fixed and movable table members, I provide a hinge construction comprising an angle 45 piece 5 fixedly secured to the table member, and provided with hinge lugs 6; a movable hinge member or casting 7, the latter being provided with lugs 8 adapted to register with lugs 6 and be connected thereto by a

50 hinge rod 9. The preferred shape of member 7 is particularly shown by Fig. 2 and, as illustrated, it is formed with a curved recessed face 10 and with a curved flange member 11. The movable table member, at 55 its inner end, is curved or rounded as shown at 12, and this curved portion is adapted to

be entered in the curved recessed face of member 7.

Rigidly secured to and movable with the movable member 7, are supporting means 60 for the movable table member 4. These supporting means, as illustrated, comprise a frame or bracket including an annular bearing member 14, arms 15, and a segmental rack 16. The movable table member 4 is 65 pivotally connected with the supporting means by a pin 17 passed through the bearing member 14 and a bearing plate 18 carried on the underside of the table member 4. 19 designates rollers interposed between 70 the said bearing members, and constitute a roller bearing on which the movable table member is mounted. This construction permits the movable table member 4 to be swung laterally on the supporting means 75 and laterally with respect to the fixed table member 1. The positions into which the movable table member may be swung are shown in dotted lines in Fig. 2.

In order to lock the member 4 in any desired position, when swung laterally relatively to the member 1, I provide a transversely extending rod 20 operable from either side of the table by means of a lever 21. Rod 20 is provided with a cam 22 85 adapted to coöperate with a curved bearing 23 secured to the underside of the movable table member 4.

The operable means for moving the movable table member 4 vertically both above 90 and below a horizontal plane include, in addition to the segmental rack 16, an operating shaft 24 having its ends supported by the legs 3. Shaft 24 is provided with hand operating wheels 25 and with a bevel gear 95 26, the latter being adapted to mesh with a gear 27 carried on an end of a worm shaft 28. The worm 29 of shaft 28 is designed to mesh with a worm wheel 30 mounted on a transversely extending shaft 31, the latter 100 having its ends mounted in bearings 32 secured to the legs 3. Shaft 31 is provided with a centrally disposed spur wheel 33, which spur wheel is adapted to mesh with the segmental rack 16.

105 From the foregoing, it will be noted that the movable member 4 may be raised and lowered relatively to the fixed member 1 into any desired position either above or below the horizontal plane of the fixed member of the table, and that the operable mechanism for raising and lowering the said

member 4 may be actuated by the hand wheels 25 from either side of the table.

34 designate depending members respectively secured to the underside of the movable member 4. These members are provided to enable an operator to swing the member 4 laterally by pressing against said members.

An extension rest 35 is provided at one 10 end of the table, and 36 designates a vertically movable extension located at the other end of the table. Extension 36 is provided with a curved depending rack member 37 adapted to engage with a cross rod 38.

15 39 designates adjustable stirrups secured to the sides of the fixed table portion 1.

What I claim is:

1. In a table of the class described, the 20 combination with a fixed member, of a movable member, operable means for supporting and moving the latter member vertically with respect to the fixed member, means pivotally connecting the movable member and the supporting means to permit a lateral 25 movement of the movable member thereon and relatively to the fixed member, and means for locking the movable member in a laterally extended position.

2. In a table of the class described, the 30 combination with a fixed table member, of a movable table member, supporting means for the movable table member positively operable means coöperating with the supporting means for moving the movable member 35 vertically, a roller bearing for the movable table member, and means pivotally connecting the latter member and the supporting means to permit a lateral movement of the movable table member on the supporting 40 means and relatively to the fixed table member.

3. In a table of the class described, the 45 combination with a fixed table member, of a movable table member, a hinge connection between said members to permit a vertical movement of the movable table relatively to the fixed table member, supporting means for the movable table member, a roller bearing for the movable table member, means 50 pivotally connecting the latter member to the supporting means to permit a lateral movement of the movable table member on

its supporting means and relatively to the fixed member, and positively operable means coöperating with the supporting means for 55 raising and lowering the movable table member.

4. In a table of the class described, the combination with a fixed table member, of a movable table member, a hinge connection 60 between the said table members to permit a vertical movement of the movable member relatively to the fixed member, supporting means for the movable member secured to a movable hinge member, and means pivotally 65 connecting the movable table member and its supporting means to permit a lateral movement of the movable table member on said supporting means and relatively to the fixed table member.

5. In a table of the class described, the combination with a fixed member, of a movable member, a hinge connection between the said members, means for supporting the movable member including a segmental rack 75 and positively operable means for moving the supporting means to raise and lower the movable member relatively to the fixed member including an operating shaft, and gearing interposed between said shaft and the segmental rack, and means pivotally connecting the movable table member and its supporting means to permit a lateral movement of the movable table member relatively to the fixed table member.

6. In a table of the class described, the combination with a fixed member, of a movable member having a rounded end portion, a hinge connection between the said members, said hinge connections comprising a 90 movable hinge member having a curved recessed face in which the rounded portion of the movable table member is entered, means for supporting the movable member, means pivotally connecting the movable table member and its supporting means, and operable means for moving the supporting means vertically.

In testimony whereof I affix my signature in presence of two witnesses.

HAROLD J. DORRANCE.
